UNITED STATES PATENT OFFICE.

JAMES FISKOW, OF MILWAUKEE, WISCONSIN.

CLOTHES-PRESSING MACHINE.

1,410,095.

Specification of Letters Patent. Patented Mar. 21, 1922.

Application filed June 14, 1921. Serial No. 477,505.

To all whom it may concern:

Be it known that I, JAMES FISKOW, a citizen of Russia, residing at Milwaukee, in the county of Milwaukee and State of Wisconsin, have invented certain new and useful Improvements in Clothes-Pressing Machines; and I do declare the following to be a full, clear, and exact description of the invention, such as will enable others skilled in the art to which it appertains to make and use the same.

My invention relates to improvements in sectional ironing boards and has for its principal object to provide a board of this character provided with novel means whereby its individual sections may be relatively moved vertically so that the required number thereof may be brought into play.

With the foregoing and minor objects in view, the invention resides in the novel construction and combination of parts hereinafter described and claimed, the descriptive matter being supplemented by the accompanying drawings.

Figure 1 is a front elevation of a pressing machine constructed in accordance with my invention, all sections of the ironing board being shown in the same plane.

Figure 2 is a view similar to Fig. 1 but illustrating the side sections of the ironing board lowered so as to expose the central section for use.

Figure 3 is a perspective view of one of the jacks by means of which the side sections of the board are raised and lowered.

Figure 4 is substantially a central vertical longitudinal sectional view.

Figure 5 is a perspective view of one of the bearing frames in which the above named jacks are pivotally mounted.

Figure 6 is a vertical transverse sectional view as indicated by line 6-6 of Fig. 1.

Figure 7 is a detail vertical transverse section as designated by line 7-7 of Fig. 1.

Figure 8 is a perspective view of one of the blocks which guide the vertical movement of the side sections of the ironing board.

In the drawings above briefly described, the numeral 1 designates a horizontal table supported by a pair of spaced legged frames 2, said frames being tied together near their lower ends by a horizontal frame structure

3 which includes a pair of parallel horizontal side bars 4.

Secured to the upper surface of the table 1 adjacent its front edge and extending transversely of said table, are two inverted T-shaped guide blocks 5 whose bases are channeled in their upper portions as indicated at 6. The channels 6 receive T-shaped guide blocks 7 which are carried by the outermost or side sections 8 of a sectional ironing board, this board being formed by said sections 8, a relatively narrow central section 9, and a one-piece board 10 which is adapted to swing over the sections 8 and 9 when the latter are in the same plane as shown for instance in Figs. 1, 6 and 7. The central section 9 is, by preference, mounted on a dove-tailed track 11 secured to the upper edges of the guide blocks 5, so that said section may be projected beyond the others as indicated in Fig. 1, whenever desirable. An appropriate support 9' is hinged to the table 1 to prevent sagging of the section 9 when the latter is projected.

For normally supporting the board sections 8 in elevated position flush with section 9, I employ a plurality of jacks 12, said jacks being preferably in the form of M-shaped frames disposed transversely beneath the ironing board and having trunnions 13 at their ends rotatably received in openings in a pair of horizontally elongated bearing frames 14, one of which is detailed in Fig. 5. These frames are suitably secured to the table 1 and their ends are preferably tied together in spaced relation by suitable rods 15. I have shown three of the jacks 12 and these jacks are connected by inclined links 16 so that when one is moved, all of the jacks will turn in a corresponding manner. For so turning the one jack, I have shown a disk 17 rotatably mounted on an appropriate standard 18 beneath the ironing board, an eccentric point of said disk being connected with the jack by a link 19, while from another eccentric point of said disk, an operating rod 19' leads to an appropriate hand lever 20 fulcrumed on the table 1. It thus follows that when this lever is operated, with the sections 8 and 9 of the ironing board in the same plane, the jacks 12 are tilted to the position seen in Fig. 2, thereby permitting the side sections 8 to lower

and expose the central section 9 for use. Coiled springs 21 surrounding guide rods 22, are preferably employed to pull the ironing board sections 8 downwardly and I intend in most instances to use another coiled spring 23 connected with the jacks 12 to assist at times in operating them.

When the board sections 8 are in their completely lowered positions, the blocks 7 10 rest on the blocks 5 as clearly shown in Fig. 2 and the lowered portions of the board are by preference additionally supported by an arched rest 24 which is preferably slotted to form a guide for the rod 19', preventing 15 any possibility of this rod buckling.

Mounted in appropriate bearings at the rear edge of the table 1, is a rotatable rod 25 connected by gearing 26 with a transverse shaft 27 which is rotatably supported 20 beneath said table, the front end of shaft 27 being provided with a crank or other handle 28 within easy reach of the operator. An L-shaped iron-carrier 29 is provided with a hub 30 through which the rod 25 is threaded, the horizontal arm of said 25 carrier 29 being disposed below the table 1 while the vertical arm thereof extends above the table to a suitable extent, this vertical arm being provided with spaced forwardly 30 extending lugs 31 in which a vertical screw 32 is rotatably mounted, the upper end of said screw being provided with a hand crank or the like 33. The screw 32 is threaded through the inner end of an iron-carrying 35 arm 34, said arm being formed of front and rear sections pivoted to each other on a vertical axis 35. The front end of the arm 34 carries an appropriate pressing iron 36 which preferably has a universal movement 40 thereon, said iron being provided with an appropriate handle 37. By adjusting the screw 32, the arm 34 may be raised and lowered as required, and the construction of said arm, together with the mounting of the 45 iron 36, will permit the latter to be manipulated in all necessary directions over the board 8-9-10, or any selected part thereof. Furthermore, it will be observed that by turning the crank 28 and consequently 50 rotating the threaded rod 25, the carrier 29 may be shifted to different positions along the ironing board.

Adjustably secured to the front end of the horizontal arm 38 of the carrier 29, is 55 an inverted T-shaped plate 39 whose base is connected by coiled springs 40 with a slide 41, the latter being mounted on an appropriate track 42 secured to the lower side of the table 1. As the screw 25 is operated to 60 shift the carrier 29, the slide 41 moves along the track 42 and the springs 40 are at all times in readiness to raise the front end of arm 38 so as to tilt the carrier 29 in such a manner as to raise the iron 36 from the 65 work.

Foot-operated means are employed to pull downwardly upon arm 38 and thereby so tilt the carrier 29 as to hold the iron 36 in tight contact with the ironing board when said iron is being used, and while this foot-operated means might assume different forms, I prefer to use the construction shown. A link 43 is pivoted to and depends from the arm 38, the lower end of said link being connected with a horizontal foot lever 75 44 which is fulcrumed at one end between ears 45 on a horizontal metal plate 46. This plate contacts with the lower sides of the bars 4 and is connected with the latter by vertical bolts 47 passing through slots 47' 80 in said bars, the upper ends of said bolts being equipped with bearings 48 slidably surrounding a pair of track rods 49 which are appropriately secured to the bars 4 (see more particularly Figs. 1 and 6). It will 85 be observed that the lever 44 is fulcrumed to the rear end of the plate 46 and the front of said plate is provided with a pair of depending ears 50 between which said lever moves. The lever is thus effectively guided 90 in its movement.

By mounting the foot lever 44 in or approximately in the manner shown and described, it may be adjusted longitudinally of the machine as the iron-carrier 29 is 95 shifted, so that regardless of the position which said carrier assumes, the foot lever is in readiness for operation in such a manner as to tilt the carrier and hold the iron 36 tightly against the work.

Preferably used in addition to the features above described, is a small pressing board 51 carried by the upper end of a rack bar 52 which slides through an opening in the table 1 and through an appropriate gear casing 53 secured to the lower side of said table. A spur gear or pinion 54 is positioned within the casing 53 and in mesh with the rack bar 52 so that by rotating it, the rack bar will be raised or lowered to 105 correspondingly move the board 51. For turning the pinion or gear 54, a shaft 55 leads forwardly from the casing 53 and is provided with a hand wheel 56. The rack bar 52 may be locked in its raised position 110 by a suitable spring-pressed bolt 57 adapted to enter the opening 58 of the rack bar 52 115 (see Fig. 4).

From the foregoing, taken in connection with the accompanying drawings, it will be 120 seen that I have produced a highly efficient and in every way desirable garment pressing device, and it may be here stated that one of the machines has been successfully constructed and used to great advantage. 125 Since all of the details shown have proven to be well adapted to the purpose for which they are designed, these details are preferably followed, but it is to be understood that within the scope of the invention as 130

claimed, numerous minor changes may be made.

No claim is herein made to features other than the sectional ironing board and the 5 means for operating its sections.

I claim:

1. A pressing device comprising a support, an ironing board above said support divided longitudinally into separate sections, 10 means fixedly mounting one of said sections on said support, a plurality of jack-forming frames pivotally mounted on said support and supporting another of said sections, links connecting said frames for movement 15 in unison, and means connected with one of said frames for rocking the same on its pivotal axis.
2. An ironing board comprising a support, a pair of blocks secured to and projecting above said support, a horizontal track extending between and secured to said blocks, a central ironing board section slidably mounted on said track for longitudinal adjustment, a pair of relatively movable 20 ironing board sections on opposite sides of said central section respectively, and means for vertically adjusting said relatively movable sections.
3. An ironing board comprising a support, a pair of spaced inverted T-shaped blocks secured to the upper side of said support, the upper sides of the T heads being provided with recesses, a central ironing board section secured to the upper extremities of said inverted T-shaped blocks, a 35

pair of relatively movable side sections disposed on opposite sides of said central section, blocks secured to the lower side of said movable sections and having portions slidably received in the above named recesses, 40 and means for vertically moving said relatively movable sections.

4. An ironing board comprising a support, a fixed central ironing board section mounted on and spaced above said support, 45 a pair of relatively movable ironing board sections at opposite sides of said central section and mounted for vertical movement, a plurality of tiltable frames mounted on the support below the free section of the ironing board and having U-shaped central portions to straddle said central section, the end portions of said frames serving to support said relatively movable sections, and means for simultaneously tilting said frames to raise 50 or lower said movable sections.

5. An ironing board comprising a support, a pair of parallel horizontally elongated frames secured to the upper side of said support, a plurality of jack frames extending transversely between said horizontally elongated frames and pivoted thereto for vertical swinging, an ironing board section resting on said jack frames and mounted for vertical movement, and means for simultaneously rocking said jack frames to vertically adjust said ironing board sections. 60

In testimony whereof I have hereunto set my hand.

JEMES FISKOW.
